DESIGN FOR A STOCKING

Application filed January 10, 1933. Serial No. 46,780. Term of patent 14 years.

To all whom it may concern:

Be it known that I, GUSTAV GASTRICH, a citizen of the United States of America, residing at Wyomissing, in the county of Berks and State of Pennsylvania, have invented a new, original, and ornamental Design for a Stocking, of which the following is a specification, reference being had to the accompanying drawing, forming part thereof.

Fig. 1 is a perspective view of the stocking embodying my novel design.

Fig. 2 is an enlarged perspective view of the foot portion of the stocking shown in Fig. 1.

Fig. 3 is a side elevational view of the foot portion of the stocking shown in Fig. 1.

Fig. 4 is a partial plan view of the foot part of the stocking shown in Fig. 1.

The essential feature of the design resides in the ornamentation in the toe, substantially as shown, comprising a design area of contrasting color or appearance with respect to the adjacent foot portions of the stocking.

I claim:

The ornamental design for a stocking as shown and described.

In testimony whereof I affix my signature.

GUSTAV GASTRICH.
